PNEUMATIC RIVET BUCKER

Filed May 6, 1926

William R. Hodges, Inventor,

By Lancaster and Allwine
Attorneys

UNITED STATES PATENT OFFICE.

WILLIAM R. HODGES, OF EUPORA, MISSISSIPPI.

PNEUMATIC RIVET BUCKER.

Application filed May 6, 1926. Serial No. 107,223.

This invention relates to an improved rivet bucker to be used to hold rivets in place during the riveting of the same.

The primary object of this invention is 5 the provision of a pneumatic rivet bucker, embodying novel structural features, which enables the same to be used with ease, and considerably less labor than the conventional manually operated bucker, for the purpose 10 of holding rivets during a riveting action.

A further object of this invention is the provision of a compact pneumatic rivet bucker, embodying an improved arrangement of parts which will best facilitate the 15 riveting action in confined quarters.

Other objects and advantages of this invention will be apparent during the course of the following detailed description.

In the accompanying drawing, forming a 20 part of this specification, and wherein similar reference characters designate corresponding parts throughout the several views,

Figure 1 is a side elevation of the improved bucker, showing the same in place in 25 a channel iron, for the purpose of holding a rivet, in a somewhat confined space, during the riveting of the channel iron.

Figure 2 is a longitudinal cross sectional view taken thru the improved pneumatically 30 operated rivet bucker, showing cooperating details thereof.

Figure 3 is a top plan view of the improved rivet bucker.

Figure 4 is a view somewhat similar to 35 Figure 1, but showing the manner in which the improved rivet bucker is adjustably used to adapt the same for various sizes of angle irons and the like.

In the drawing, wherein for the purpose 40 of illustration is shown only a preferred embodiment of this invention, the letter A may generally designate the improved rivet bucker, which is adapted to be used upon channel irons or like structural pieces, for 45 the purpose of holding rivets C in place. The improved rivet bucker A is of the pneumatic type, and embodies a cylinder D, within 50 which a plunger construction E operates; a handle F being provided for holding the bucker A, and as a means to feed the fluid

for operating the plunger E. The cylinder construction D is formed to detachably receive different sizes of stingers G, D' and G'', etc.

The cylinder D is preferably hollow cylindrical in formation, including the cylindrical body portion 10, having the plunger compartment 11 therein. At its upper edge the body portion 10 is provided with an in-turned annular slightly upwardly sloping 55 plunger retaining flange 12, defining a downwardly facing shoulder 13 which faces downwardly towards the compartment 11, the flange 12 being provided to define a restricted passageway 14 axially aligning with 60 the compartment 11, and thru which the plunger also operates. The cylinder body 10 is open at the lower end thereof, being internally screw threaded at 16, for detachably receiving a base 17. The base 17 includes the 65 reduced screw threaded shank or portion 19 adapted to be detachably threaded in the screw threaded opening 16, and it also includes a polygonal shaped wrench engaging head 20 adapted to lie below the lower edge 70 of the cylinder body 10, and to compress a gasket 21 against the body 10, to provide a leak proof connection between the base 17 and body 10. The cylinder 10 radially 75 thereof is provided with a tubular boss 25, 80 having a screw threaded opening 26 therein which communicates with the compartment 11, just above the top surface 28 of the base 17, when the latter is in place to its maximum extent in the cylinder 10. This screw 85 threaded opening 26 is adapted to receive the screw threaded end of the handle F, as will be subsequently described.

The plunger construction E preferably includes the enlarged piston head 35, slid- 90 able in the compartment 11; and the plunger stem 37 connected integral with the head 35, although of less diameter than the same, and slideable thru the opening 14 at the upper end of the cylinder body 10. At the juncture of 95 the stem 37 and piston head 35, a shoulder 38 is formed which is adapted to abut against the shoulder 13 of the cylinder 10, to limit the outward movement of the piston plunger E. The piston head 35 is preferably an- 100

nularly grooved with any approved number of grooves, adapted to receive piston rings 40, or analogous packing. The lower end of the piston 35 is preferably provided with a 5 reduced extension formed by tapering the piston head downwardly in a converging relation, so that when the piston head 38 seats upon the top surface 28 of the base 17, an annular space 42 will be provided below 10 the piston head 35, into which the fluid may flow for the purpose of lifting the plunger within the cylinder.

At its upper end the plunger stem 37 is preferably provided with a reduced socket 15 extension 45, which has therein a cup-shaped recess 46, the axis of which is eccentric to the axis of the plunger E, and which may be formed on any approved radius, the same being adapted to receive the head of 20 the rivet in the relation illustrated in Figure 1 of the drawing. If preferred, some means may be provided upon the cylinder D to guide the action of the plunger E to a limited straight line movement, so that the 25 center of the socket 46 is always disposed directly at the opposite side of the axis of the plunger D with respect to the handle F, since this is the position which the parts assume during a riveting action, in order to 30 best adapt the tool for use in cramped and close quarters, as illustrated in Figures 1 and 4.

The base 17 inwardly of the bottom surface thereof is provided with a screw 35 threaded opening or socket 50, adapted to detachably receive the upper screw threaded end 52 of the stinger G. The stinger G may be made in any approved length, and various lengths of stingers will 40 have to be provided, all of which are provided with the screw threaded end 52, or analogous means for detachably fitting in the socket 50. In lieu of the screw threaded connection a bayonet slot connection, or any 45 analogous approved means for connecting the stinger in the base may be provided. The stinger G at its lower end is pointed at 50, for digging into a structural part to be riveted. The screw threaded socket 50, and 55 the axis of the stinger G are arranged eccentric to the axis of the plunger E, at the opposite side of the axis of the plunger E, with respect to the attachment handle F. In fact, the axis of the stinger G aligns with 60 the axis or center of the socket 46, of the plunger, as is illustrated in the drawing, in order that the tool may be practically used in close quarters.

Referring to the handle F, the same includes a tubular body 60, which may be of 65 any approved construction, but which preferably tapers from an enlarged diameter at its free end to a reduced diameter at its cylinder connected end. This body 60 is

provided with a duct 61 longitudinally therethrough, thru which the fluid, either air or liquid, may flow to operate the improved tool. The handle at its cylinder connected end is provided with a screw threaded shank 65 adapted to connect in the screw threaded opening 26 above mentioned, and at its free end the handle body 60 may be provided with a reduced shank 63, for detachably receiving a flexible or other fluid conducting conduit 64, as by means 65.

Transversely in the handle body 60, preferably adjacent the free end thereof, it is preferred to provide a valve seat opening 66, within which a regulating valve 67 is provided, of any approved type, having a suitable way therethrough for regulating the flow of the operating fluid along the passageway 61 into the cylinder. Between this valve 67 and the cylinder it is preferred to provide a release valve 70 of any approved construction, which is provided for releasing the air or liquid pressure from the tool, after a bucking operation.

From the foregoing description of this invention the operation will be apparent. 90 While the tool is termed a pneumatic tool, it is within the contemplation of the invention to utilize liquid as an operating medium. The handle body 60 serves a dual function in providing for conduction of the operating 95 medium, and which the operator grasps in order to handle the tool. This handle is arranged at right angles to the axis of the cylinder, and it may be conveniently operated as a consequence. As is illustrated in 100 Figure 1 of the drawing, the tool may be practically used within the close quarters of a channel iron B, for the purpose of bucking the head 75 of a rivet C, during the riveting action. As is illustrated in Figures 1, 2 and 4, various sizes of stingers may 105 be applied, merely by detachment and attachment with respect to the base 17.

Various changes in the shape, size, and arrangement of parts may be made to the 110 form of invention herein shown and described, without departing from the spirit of this invention or the scope of the claims.

I claim:

1. As an article of manufacture a plunger 115 for pneumatic rivet buckers comprising a piston portion of cylindrical formation having one end thereof tapered on a decreasing diameter to a flat surface, the opposite end of the piston portion having a reduced stem axially extending therefrom, the reduced stem at its free end having a socket eccentrically disposed with respect to the axes of the stem and piston portion.

2. In a pneumatic rivet bucker the combination of a cylinder having a chamber 125 therein, a piston slidable in said chamber having a stem extending from one end of

the cylinder and provided with a socket therein, the opposite end of the cylinder having a base thereon, a stinger on said base, a handle having a duct connection with the chamber of the cylinder immediately at the bottom of the cylinder substantially flush with the inside surface of the base facing the chamber, said piston having the end

thereof facing the base beveled so that when the piston engages against the base there will be an annular space in the chamber surrounding the bevel portion of the piston into which the duct communicates for admission of an operating fluid.

WILLIAM R. HODGES.
